CLAIM
The ornamental design for x-control measuring gauge, as shown and described.

DESCRIPTION

FIG. 1 is a perspective view with all sides being identical of a x-control measuring gauge showing my new design, drawn on a slightly enlarged scale;

FIG. 2 is a elevational view showing one of the four identical side views;

FIG. 3 is a top plan view; and

FIG. 4 is a bottom plan view thereof.

Fig. 1.

Fig. 2.

Fig. 3.
